UNITED STATES PATENT OFFICE.

THOMAS H. JOHNS, OF ETOWAH, TENNESSEE.

DESIGN FOR A ROAD SIGN.

Application filed August 15, 1928. Serial No. 27,823. Term of patent 14 years

To all whom it may concern:

Be it known that I, THOMAS H. JOHNS, a citizen of the United States, residing at Etowah, in the county of McMinn and State of Tennessee, have invented a new, original, and ornamental Design for a Road Sign, of which the following is a specification, reference being had to the accompanying drawing, forming part thereof.

I claim:

The ornamental design for a road sign, as shown.

THOMAS H. JOHNS.
